CARD FILING EQUIPMENT

George C. Bruen, deceased, late of Chicago, Ill., by Sophie E. Bruen, executrix, Chicago, Ill., assignor of seventy and five-tenths per cent to said Sophie E. Bruen, five per cent to Edna V. Dickinson, Highland Park, Ill., nine per cent to Sarah M. Bullock, Wilmette, Ill., ten and five-tenths per cent to G. A. Stuart, Denver, Colo., two per cent to Jay Fisher, Chicago, Ill., one per cent to Marie Thoenen, Elmwood Park, Ill., one per cent to George H. Fredericksen, Chicago, Ill., and one per cent to E. M. Thorsen, St. Joseph, Mo.

Application August 28, 1946, Serial No. 693,456

4 Claims. (Cl. 129—43)

1

The present invention relates to card filing equipment and more particularly to a card file of the type comprising a base to which is attached an invertible card-holding tray—the base and tray forming, conjointly, when closed, a substantially dust-proof housing which is adapted to be mounted on a desk top and which can be opened without occupying any more desk space than is required when the file is closed.

The subject matter of this application is closely related to that of the copending application of George C. Bruen, Serial No. 682,679, filed July 10, 1946, for Card filing equipment, and the improvement herein dealt with has to do with a simplified mechanical arrangement for interconnecting the base and card-holding tray, while enabling easy rotation of the tray from open to closed position and vice versa.

The object of the present invention is to provide a card file of the type indicated which is substantial and durable, easily operated and unlikely to get out of order, and which can be produced economically.

In the drawings which accompany this specification:

Fig. 1 is a perspective view of the improved card file with the card-holding tray in closed position;

Fig. 2 is a plan view of the card file with the card-holding tray open;

Fig. 3 is a transverse section taken substantially on a line 3—3 of Fig. 2;

Fig. 4 is an enlarged transverse section taken substantially on a line 4—4 of Fig. 2;

Fig. 5 is a detail view of the card-holding track;

Fig. 6 is a side elevational view showing the card file with the card-holding tray in its inverted or closed position, as in Fig. 1;

Fig. 7 is a side elevational view depicting a step in the operation of turning the card-holding tray from the closed position of Fig. 6 to the fully open position of Fig. 10;

Fig. 8 is a side elevational view illustrating a further step in the operation of turning the card-holding tray;

Fig. 9 is a side elevational view depicting a still further step in the operation of turning the card-holding tray, and shows the tray nearly in its fully opened position of rest;

2

Fig. 10 is a side elevational view showing the card file fully opened; and

Fig. 11 is a side elevational view of an alternative structure and depicts a modification in the manner of linking the base and tray together.

The turning operation depicted by successive steps in Figs. 6 to 10, inclusive, is reversible for closing the file.

The major components of the illustrated structure are a base 10 and a card-holding tray 9. The base 10 preferably takes the form of a channel, as shown, open at both ends and consisting of two side walls 11 and 12 and a bottom 13. The two side walls are rabbeted at their inside upper edges, as indicated at 14 and 15 in Fig. 4, to provide clearance for a pair of elongated rigid links 16 and 17.

Tray 9 comprises a flat bottom 18, two side walls 19 and 20 and two end walls 21 and 22, which are higher than the side walls.

Secured to the bottom of the tray, interiorly thereof at one end extending transversely of the tray is a rectangular block 23 which is notched at 23a, as shown in Figs. 3 and 4, to receive the closed end of a U-shaped card-carrying track 24 (see Fig. 5), consisting of a metal rod of round cross section bent as shown and comprising two parallel spaced legs 25, 26 and an integral cross member 27.

Also secured to the bottom of the tray interiorly thereof and at the end remote from block 23 is a second rectangular block 28 which likewise extends transversely of the tray. Block 28 is provided on its upper surface with a pair of notches 29 and 30 in which are removably seated the two free ends of the legs 25 and 26 of the card-carrying track. Notches 23a, 29 and 30 are so positioned that track 24 is supported at a suitable distance above the bottom of the tray. The cards, not shown, are mounted in the usual manner on track 24 by means of suitable notches in one edge of each card—which accords with conventional practice. With the cards thus attached to track 24 and the tray inverted as hereinafter described, the cards will hang in suspension from the track.

Superimposed upon the block 28 is an elongated rectangular slide 31 having a pair of elongated openings 32, 33 which accommodate a pair of wood screws 34, 35—the latter being threaded

into block 28 and serving to hold slide 31 in place, while permitting a limited lengthwise movement thereof.

A pair of notches 36 and 37 cut through the inner edge of slide 31 are adapted to register with notches 29 and 30 when slide 31 is moved to the left, as viewed in Fig. 4, whereby to permit the free ends of legs 25 and 26 to enter notches 29 and 30 and to be withdrawn therefrom. However, slide 31 is normally held in the track-retaining position, in which it is shown in Fig. 4 by a biasing spring 38 seated in a recess 39 in the block 28 and bearing against a pin 40 which is fixedly secured to slide 31 and extends downwardly into recess 38. Track 24 can be bodily removed from the tray, even with the cards attached, by moving slide 31 to the left, as viewed in Fig. 4, sufficiently to bring notches 36 and 37 into registration with notches 29 and 30, respectively; and said track can be just as easily replaced following a like manipulation of the slide.

When the tray is in open position, the bottom 18 thereof rests on the bottom 13 of the base, and, in order to suppress the noise which might otherwise result from dropping the tray onto the base, a layer 41 of sheet felt or other sound-deadening material should be secured to the top surface of bottom 13.

The two links 16 and 17 disposed at either side of the tray are each pivotally connected at one end to the base and at the other end to the tray. In the embodiment of Figs. 6 to 10, inclusive, each link is connected to the base at a point midway of its ends, and to the tray at a point near one end—that is to say, remotely from the midpoint of the tray. In the modification of Fig. 11, the links, such as 16a, are connected to the tray at a point midway of its ends and to the base at a point remote from its midpoint. These two alternative arrangements are fully equivalent one to the other for all practical purposes.

Figs. 6 to 10 illustrate in progressive steps the manner in which the card-holding tray may be lifted from closed position and rotated end-over-end and brought to rest on the base in open position, the links serving both to prevent detachment of the tray from the base and to position the tray on the base lengthwise thereof irrespective of which way it is turned.

The arrangement of Fig. 11 operates in the same manner as that of Figs. 6 to 10, except that with the arrangement of Fig. 11, it is not necessary to lift the tray as high, in effecting a reversal, as is the case with the arrangement of Figs. 6 to 10.

It will be apparent that the present invention provides a very simple and inexpensive mechanism for accomplishing its objective, and one which is devoid of any inherent disposition to get out of order.

While the structure illustrated is built principally of wood, it will be self-evident that the invention is equally applicable when the base and tray are made of sheet metal.

Having thus described this invention, what is claimed as new and sought to be secured by Letters Patent of the United States, is:

1. A card file comprising, in combination, a base member having side walls secured to a bottom in opposed relationship and having open ends, a tray member having ends and side walls secured to a bottom and of a size to nest between

the side walls of the base member with the ends of the base member substantially flush with the outer surfaces of the tray end walls, the heights of the side walls of the base and tray members being such that they are substantially flush when the bottom of the tray member rests on the bottom of the base member, the heights of the ends of the tray member being so related to the heights of the side walls that said ends rest against the bottom of the base member and support the tray member with the side walls of the members in partially overlapping relationship when the tray member is inverted relative to the base member, and said members being connected together for endwise swinging movement of one member relative to the other between inverted positions by substantially rigid and parallel links having their opposite ends coaxially connected for rotational movement to each of the members, said links being connected at one end to the longitudinal mid-portions of opposite sides of one of the members near one edge thereof, and the other ends of said links being connected to the sides of the other member at positions near one of the ends thereof.

2. A card file comprising, in combination, a base member having side walls secured to a bottom in opposed relationship and having open ends, a tray member having ends and side walls secured to a bottom and of a size to nest between the side walls of the base member, said end walls having a height exceeding that of the side walls of both members and being so related thereto that said end walls rest upon the bottom of the base member to form end closures and support the tray member with the side walls of the members partially overlapping when the tray member is inverted relative to the base member, and said members being connected together for endwise swinging movement of one member relative to the other by links in laterally opposed relationship, said links being coaxially connected at their opposite ends to the sides of the members at fixed positions such that in either an upright or vertical position of the tray member relative to the base member the links extend longitudinally along substantial portions of the upper inner marginal portions of the base member side walls.

3. A card file as defined in claim 2, and wherein in corresponding ends of said links are rotatably connected to the outsides of the tray member side walls at positions adjacent the marginal edges thereof remote from the bottom.

4. A card file as defined in claim 2, and wherein in corresponding ends of said links are connected for rotational swinging movement to the insides of the base member side walls at positions adjacent the marginal edges thereof remote from the bottom.

SOPHIE E. BRUEN,

Executrix of the Last Will and Testament of George C. Bruen, Deceased.
